PNEUMATIC TOOL

Louis Francis, Union City, N. J., assignor of
one-half to Mary Leinster Francis, Union
City, N. J.

Application March 4, 1944, Serial No. 525,075

4 Claims. (Cl. 121—17)

1

This invention relates to pneumatic tools.

An object of this invention is to provide a valveless pneumatic tool which can be designed for either light or heavy work and which is operated from a fairly low fluid pressure, the fluid being preferably air.

Another object of this invention is to provide a tool of this kind wherein the prime mover consists in air acting against a flexible apertured diaphragm, the aperture of the diaphragm being alternately closed and opened by reciprocating movement of a spring-pressed plunger having a valve-like head. The degree of air pressure against the diaphragm acts as a regulating medium for regulating the length of the stroke of the plunger, and the head on the diaphragm being so constructed that the air pressure will force the head away from the diaphragm thereby permitting exhausting of the air.

A further object of this invention is to provide a pneumatic tool which can be made either out of light metal or almost entirely out of wood, the device being valveless will not require close tolerances, and in one form of the invention, the spring for the plunger acts as a guide for the plunger while simultaneously providing a tensionable means to move the plunger on the return or inoperative stroke thereof.

A further object of this invention is to provide a pneumatic tool of this type which by reason of its simple construction can be produced at very low cost, thereby providing a tool which is practical for small jobs and can also be used for large or heavy jobs, the tool being of such construction that it can be operated by pressure generated by a person or by pressure from other pressure source.

With the foregoing objects and others which may hereinafter appear, the invention consists of the novel construction, combination and arrangement of parts as will be more specifically referred to, and illustrated in the accompanying drawings wherein are shown embodiments of the invention, but it is to be understood that changes, variations and modifications may be resorted to which fall within the scope of the invention as claimed.

In the drawings:

Figure 1 is a detail side elevation of a pneumatic tool constructed according to an embodiment of this invention.

Figure 2 is a detail front elevation partly broken away and in section of the tool.

Figure 3 is a sectional view taken on the line 3—3 of Figure 2.

2

Figure 4 is a detail side elevation of a modified form of this invention.

Figure 5 is a sectional view partly in elevation taken on the line 5—5 of Figure 4.

Figure 6 is a vertical section partly in detail of another form of this invention.

Figure 7 is a sectional view taken on the line 7—7 of Figure 6, and

Figure 8 is a modified form of handle for use with the invention shown in Figures 1 and 2.

Referring to the drawings and first to Figures 1, 2 and 3, the numeral 10 designates generally a frame or handle which includes a pair of forwardly convergent frame members 11 and 12 which may, if desired, be integral with each other and which terminate at their forward ends in a truncated V-shaped body 13.

The frame members 11 and 12 at their upper or rear ends are connected together by a connecting member 14 which may be integral with the upper or divergent ends of the frame members 11 and 12. The body 13 is formed centrally thereof with a bore 15 and a plunger, generally designated as 16, which is formed of an elongated rod 17 and a head 18 is slidable in the bore 15.

A block or annular body 19 is positioned adjacent the upper or divergent ends of the frame members 11 and 12 and is formed on the forward or lower side thereof with an air chamber 20. The block or body 19 is formed centrally thereof with an air intake opening 21 and an air pipe 22 communicates with the opening 21 and is adapted to be connected to a suitable source of air or gas pressure supply. A spring-pressed valve 23 is interposed in the pipe 22 and includes a button 24 which is spring-pressed to hold the valve 23 in normally closed or cut off position. The body 19 is positioned between a pair of cutouts 24a and 25 which are formed in the inner sides or edges of the frame members 11 and 12.

A cup-shaped resilient diaphragm 26 engages against the lower or outer end of the body 19 and is formed centrally thereof with an opening 27 so that air from the chamber 20 may be released from the chamber when the head 18 moves downwardly on its operating stroke. A flanged cap 28 is threaded onto the block or body 19 and tightly holds the diaphragm 26 against the lower end of the block 19.

A spring 29 is disposed about the rod 17 bearing at one end against the lower side of the head 18. The spring 29 extends through the bore 15 and constitutes a guide for the rod 17. The spring 29 is tensioned and tightly held within the

bore 15 by means of a plate 30 which is secured to one side of the body 13 by fastening members 31. The plate 30 on the inner face thereof is formed with a groove 32 within which the convolutions of the spring 19 engage and the plate 30 may be loosened so as to adjust the endwise position of the spring 26, in order to provide for the desired tension on the spring 29.

The plunger rod 17 at its lower or operating end has threaded thereon a cap or coupling member 33. The coupling member or cap 33 is formed with interior threads 34 and an impact tool or chisel 35 is threaded into the lower end of the cap 33. The tool 35 may be of any desired shape being shown as pointed at its operating end, but it will be understood that this tool may be flat or in the form of a chisel, or may be formed with a rivet forming or upsetting lower end.

A handle 36 is disposed at the upper end of the frame 10 and the handle 36 has secured thereto a pair of dowels or pins 37 which are slidable in openings 38 formed in the upper ends of the frame members 11 and 12. The pins or dowels 37 have extending transversely therethrough limiting pins 39 which are slidable in elongated slots 40 formed in the arms or frame members 11 and 12. The handle 36 is cushioned with respect to the frame 10 by means of a pair of springs 41 which engage about the pins or dowels 37 and at their lower or outer ends are seated in sockets 42 concentric to the openings 38.

Referring now to Figures 4 and 5, there is disclosed a modified form of this pneumatic tool which may be made quite small for use with relatively low air or gas pressure. The tool disclosed in Figure 5 includes an elongated guide which is formed with a central bore 44. A pair of oppositely extending arms 45 are carried by or formed integral with the upper end of the guide 43 and an annular member 46 is secured between the upper ends of the arms 45. The annulus 46 is formed with interior threads 47 and is provided at its lower end with an annular flange 48. A plug 49 is threaded into the annulus 46 from the upper end thereof and is formed on the lower side thereof with an air chamber 50.

A disc-shaped and inwardly cupped diaphragm 51 is adapted to seat on the flange 48 and is tightly held on the flange 48 by the plug 49. A washer 52 is interposed between the lower end of the plug 49 and the upper side of the diaphragm 51. A tube 53 is connected to the plug 49 centrally thereof and communicates with the chamber 50. A wing nut 54 is fixed relative to the tube 53 so that the plug 49 may be readily adjusted or removed with respect to the annulus 46. A hose 55 engages the upper end of the tube 53 and may be connected to any suitable source of air pressure. In practice the tool herein disclosed is sufficiently small so that the air pressure generated in the lungs of a person may readily operate the device.

A plunger generally designated as 56 is adapted to be reciprocated by the air pressure in the chamber 50 and also by means of a spring 57. The plunger 56 includes an elongated plunger rod 58 which is slidable in the guide 43 and terminates at its lower end in a threaded portion 59 so that any desired tool may be mounted on the lower end of the rod 58. A cup-shaped head 60 is secured to the upper end of the rod 58 and bears against the diaphragm 51, the latter having a central opening 61 which is normally closed when the head 60 is in contact with the lower or outer side of the diaphragm 51.

Referring now to Figures 6 and 7, there is disclosed a pneumatic tool which may be designed for fairly heavy duty. The tool shown in Figures 6 and 7 includes a housing 62 which is formed with a cylindrical flange 63 having exterior threads 64. The flange 63 forms an air chamber 65 within the housing 62 and a flexible diaphragm 66 engages against the lower end of the flange 63. The diaphragm 66 is tightly held against the lower end of the flange 63 by means of a flanged cap 67 which is threaded onto the flange 63. The housing 62 also includes a reduced diameter nipple 68 having exterior threads 69 on which a cap 70 is threaded. A gasket 71 is interposed between the cap 70 and the upper end of the nipple 68. The cap 68 has secured centrally thereof upwardly extending elongated guide tube 72 within which an elongated plunger rod 73 is slidably mounted.

The rod 73 has secured thereto at a point intermediate the length thereof a cup-shaped head 74 which is adapted to engage against the lower or outer side of the diaphragm 66, the latter having a central opening 75 through which the rod 73 extends and which provides for release of air from the chamber 65. The rod 73 at its lower end is formed with a tool or cutting head 76 but it will be understood that if desired the lower end of the rod 73 may be threaded after the manner of the rod 17 for detachably receiving a suitable tool. The rod 73 is constantly urged upwardly to maintain the head 74 against the diaphragm 66 by means of a spring 77. The spring 77 is disposed within the tube 72 and is connected at its lower end to the upper end of the rod 73 and is connected at its upper end to a transversely extending pin or bolt 78 extending through the tube 72. A cap 79 is also threaded on the upper end of the tube 72 so as to close this upper end.

The air chamber 65 is connected to a source of air pressure supply by means of a pipe 80 which is connected to the housing 62 and communicates at one end with the chamber 65. The other end of the pipe 80 is adapted to be connected to a suitable source of air or gas pressure supply. A spring-closed valve 81 is interposed in the pipe 80 and has an operating handle or knob 82 positioned at a point convenient for engagement by one hand or finger of the operator.

In order to provide for relieving the hand of undue vibrations which are caused when the valve 81 is opened and the plunger, which includes the rod 73 and the head 74, is rapidly vibrating, I have provided a handle 83 which is slidable on the tube 72. The handle 83 is cushioned with respect to the tube 72 by means of a lower spring 84 and an upper spring 85. The two springs 84 and 85 hold the handle 83 in a neutral position and will permit vibration of the tool when the valve 81 is opened without communicating such vibration to the hand of the operator.

Referring now to Figure 8, there is disclosed a modified form of cushioning means for the tool shown in Figures 1 and 2. In the present instance, the frame 10a has fixedly secured to the upper end thereof a handle 36a. A longitudinally bowed spring 86 engages the upper side of the handle 36a and is formed at the opposite ends thereof with elongated slots 87. A screw or fastening member 88 extends through the slots 87 and into the opposite end portions of the handle 36a so that the central or bowed portion of the spring 86 may be flexed inwardly thereby cush-

ioning the vibrations of the frame 10a within the hand of the operator.

In the use and operation of this tool, the several forms operate in a similar manner. The tool or head 35 is engaged with the desired article and the handle 36 grasped in one hand with a thumb or finger pressed against the button 24. When the button 24 is pushed inwardly, the chamber 20 will be communicated with the source of air or gas pressure supply and pressure in chamber 20 will flex the diaphragm 26 outwardly. The air pressure will also be sufficient to move the head 18 out of contact with the lower or outer side of the diaphragm 26 so that the upper side of the head 18 which also constitutes a valve will be disengaged or unseated and the air from the chamber 20 will be exhausted through the diaphragm opening 27.

Spring 29 will return the plunger 16 to provide for engagement of the head 18 with the diaphragm 26 which will be flexed inwardly by the impact of the head 18 and the tension of the spring 29. The air pressure in the chamber 20 will immediately be built up sufficiently to again move the plunger 16 outwardly or downwardly on its operating stroke and in practice the plunger 16 will vibrate at a very rapid rate. The length of the stroke of the plunger 16 will depend in great part not only upon the tension of the spring 29 but also upon the degree of air pressure present in chamber 20.

This tool provides a valveless pneumatic tool which may be made either substantially entirely out of wood or light metal and in practice, the tool is designed as a fairly light tool but if a heavier tool is desired, it is only necessary to add weight to the frame 10 or to make the frame 10 out of heavier metal, such as steel or the like. The amount of air pressure necessary to vibrate the plunger 16 can be regulated in part by the flexibility of the diaphragm 26. In other words, where a fairly low air pressure is available, the diaphragm 26 may be made out of quite thin rubber or other flexible material.

Where heavy air pressure is available the diaphragm 26 may be made fairly thick. In the event the diaphragm 26 should become worn or split, a new diaphragm can easily and quickly be inserted by unthreading the flange cap 28, the plunger 16 being pulled outwardly so as to disengage the head 18 from the diaphragm. The new diaphragm may be mounted in place of the worn diaphragm and the cap 28 replaced.

Where the plunger 16 is made out of wood, the exterior of the rod 17 may be coated with graphite or other suitable lubricant so that the rod 17 will freely slide within the spring 29. This tool has been designed for use in chipping rust, upsetting rivets of either small or large size, and may also find varied uses where a vibratory tool can be used. It will therefore be understood that I do not wish to be limited to the use of this tool as a tool for only chipping rust, driving nails, upsetting rivets or the like.

It will be understood that the term "pneumatic tool" or "tools" as used herein contemplates any device or mechanical application of the disclosure made herein wherein the prime mover consists in air or other fluid pressure acting against a flexible apertured diaphragm as hereinbefore described.

What I claim is:

1. A pneumatic tool comprising a frame formed of a forward body, a pair of spaced arms extending rearwardly of said body, said body having a lengthwise bore, a plunger formed of a stem slideable in said bore and a head movable between the inner edges of said arms, a housing fixed between said arms rearwardly of said body, said housing being formed of a pressure chamber and a diaphragm having a central exhaust opening, means communicating said chamber with a source of pressure supply, and spring means about said stem constantly urging said plunger rearwardly into contact with said diaphragm for normally closing said opening.

2. A pneumatic tool as set forth in claim 1 which includes means whereby said spring means may be tensioned.

3. A pneumatic tool comprising an annular housing, a flexible diaphragm having a central opening mounted in one end of said housing, a tubular guide extending from the opposite end of said housing, a reciprocable plunger including an elongated rod extending through said housing and having one portion thereof slideable in said tubular guide, a head fixed to said rod and normally engaging against said diaphragm for closing said opening, spring means in said guide connected to said rod for normally holding said head against said diaphragm, and means connecting said housing with a source of fluid pressure supply.

4. A pneumatic tool comprising a frame formed of a forward body, a pair of spaced arms extending rearwardly of said body, said body having a lengthwise bore, a plunger formed of a stem slideable in said bore and a head movable between the inner edges of said arms, a housing fixed between said arms rearwardly of said body, said housing being formed of a pressure chamber and a diaphragm having a central exhaust opening, means communicating said chamber with a source of pressure supply, and spring means about said stem constantly urging said plunger rearwardly into contact with said diaphragm for normally closing said opening, said spring means being snugly disposed in said bore and constituting a bearing for said stem.

LOUIS FRANCIS.
